[57] CLAIM

The ornamental design for a combined square and tape measure, as shown and described.

DESCRIPTION

FIG. 1 is a front and bottom-left isometric view of combined square and tape measure showing my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a front and bottom-left isometric view thereof with the tape measure in a folded position.

FIG. 1

FIG. 2

FIG. 3

FIG. 4

FIG. 5

FIG. 6

FIG. 7
